UNITED STATES PATENT OFFICE.

HARRY F. SCHWARTZENBERG, OF CHICAGO, ILLINOIS, ASSIGNOR TO WILLIAM H. MINER, OF CHICAGO, ILLINOIS.

DRAFT-YOKE FOR RAILWAY-CARS.

1,128,374.

Specification of Letters Patent. Patented Feb. 16, 1915.

Application filed March 9, 1914. Serial No. 823,281.

To all whom it may concern:

Be it known that I, HARRY F. SCHWARTZENBERG, a citizen of the United States, residing at Chicago, in the county of Cook and State of Illinois, have invented a certain new and useful Improvement in Draft-Yokes for Railway-Cars, of which the following is a full, clear, concise, and exact description, reference being had to the accompanying drawings, forming a part of this specification.

My invention relates to improvements in draft yokes for railway car draft rigging.

The object of my invention is to provide a draft yoke adapted to be readily engaged to or disengaged from a draw bar.

In the drawings forming part of this specification, Figure 1 is a plan view of draft yoke embodying my invention; Fig. 2 is a side elevation thereof; Fig. 3 is a cross section taken on line 3--3 of Fig. 2; Fig. 4 is a longitudinally vertical section on line 4--4 of Fig. 1.

Referring to the drawings, the numeral 5 indicates a U-shaped draft strap having an upper limb 6 and lower limb 7, a connecting member 8 for said limbs, a filler block 9 secured thereto preferably by a rivet 10.

The numeral 11 designates a draw bar of the standard type only the rear portion thereof being shown in the drawings. The butt 12 of the draw bar is provided with oppositely arranged shoulders 13--13, the said shoulders being engaged by shoulders 14--14 of the limbs of the yoke, the said shoulders 14--14 being formed by the inward turning of the limbs of the yoke strap near its forward free ends. The limbs of the yoke strap are forwardly extended from the inward turned portion, as illustrated clearly in Fig. 4 of the drawings, forming the jaw members 15--15, which are in preferable construction adapted to engage at their ends against the adjacent face of the draw bar. In preferable construction, the jaw members 15 forwardly converge and are adapted to receive a surrounding member 16 which is secured to the draw bar by the coupler key 17 passing transversely therethrough.

50 The surrounding members 16 preferably comprises a pair of oppositely arranged U-shaped bands 18--18 having overlapping ends provided with registering perforations 19--19 alined with the transverse slot 20 in

55 the draw bar for the passage of the coupler

key 17. In preferable construction each of the U-shaped members 18 has an extending flange 21 upon each leg thereof to provide sufficient surface for the suitable arrangement of the perforation 19 therethrough. 60 The rear edges 22--22 of the surrounding member 16 engage in preferable arrangement against the forward faces 23--23 of the in-turned portions of the limbs of the yokes. In assembling the yoke and draw 65 bar the yoke strap 5 is placed in position upon the draw bar, the shoulders 14 thereof engaging against the draw bar shoulders 13, the U-shaped members are placed in their opposed relation upon the forward in-turned jaw members of the yoke, and the key 17 is passed through the registering perforation in the U-shaped members and draw-bar. To disengage the draw bar 70 from the yoke, the operation is reversed. 75 Upon forward pull of the draw bar, the shoulders of the yoke are held in engagement against the shoulders of the draw bar by the U-shaped members 18, the coupler key 17 preventing separating movement of 80 the two U-shaped members. On rearward movement of the draw bar the butt thereof is adapted to engage directly against a front 85 filler or the front end of the pressure resisting member within the yoke. 85

I claim:

1. In a draft rigging for railway cars, the combination with a draw bar having the usual shoulders on top and bottom thereof, of a yoke having the limbs thereof provided with inwardly extending shoulders near the front ends thereof, said shoulders engaging and coöperating with the draw bar shoulders, the ends of said yoke being also forwardly and inwardly extended in front of the shoulders thereon, said extensions bearing against the draw bar shank, and means for holding the yoke in position on the draw bar, said means including two U-shaped members having over-lapped slotted sides, each of said members having an inclined wall fitting over the said ends of the yoke strap in front of the shoulders thereon, and a key passing through said U-shaped members and the draw bar. 95

2. In a draft rigging for railway cars, the combination with a draw bar having shoulders on the top and bottom thereof, a yoke provided with shoulders at the front 100

110

ends of the arms thereof, said shoulders co-operating with the draw bar shoulders, said yoke being provided also with jaw members in front of said shoulders formed thereon, a pair of U-shaped members inclosing said jaw members, said U-shaped members having over-lapped sides and being also counter

parts, and a key passing through slots in said over lapped sides and the draw bar.

HARRY F. SCHWARTZENBERG.
